MACHINE FOR DRAWING THREADS
FROM FABRICS

Jacques Ollenderff, Paris, France, assignor to
Anciens Etablissements R. Cornely & Cie.,
Société Anonyme, Paris, France, a company of
France

Application February 16, 1932, Serial No. 593,349
In France February 21, 1931

7 Claims. (Cl. 112—78)

In machines for drawing the threads from fabrics, the feeding and the stretching of the fabric play an all important part, because, on the one hand, it is necessary that the fabric should be fed in a direction strictly parallel to that of the threads to be drawn, the feed motion being interrupted during the action of the thread drawing tool, and, on the other hand, the fabric should be continuously maintained well stretched in order that the thread drawing tool may not meet with the threads parallel to its plane and may draw, during its downward motion, only the threads that should be drawn.

Furthermore, the fabric must be kept stretched along a certain length after it has moved past the thread drawing tool, or, otherwise, the threads parallel to the plane of the thread drawing tool and located in the part of the fabric in which the other threads have already been drawn might sag as low as the line of action of the knife which cuts off the drawn threads, and be also cut off thereby.

On the other hand, it is important that the stretching organ should not interfere with the feed mechanism.

It is also useful to be capable of accurately adjusting the feed according to each kind of fabric so as to allow the thread drawing tool to pass exactly between the threads parallel to its plane.

In the known machines for drawing threads from fabrics, the feed of the fabric is obtained by means of two kinds of systems:

(a) Systems comprising a driving band or grip and a presser foot. In that case, the driving band or grip is generally located under the work plate, which leaves but small room under the table of the machine for the knife controlling mechanism and for the movement of the cutter knife.

(b) Systems comprising rollers generally located above the work plate and which are given a uniform rotary motion, which causes the fabric to move forward during the action of the thread drawing tool and of the cutter knife. The stretching of the fabric is then obtained either through stationary devices, that is devices independent of the feed, and consequently interfering therewith, or through a special arrangement of the driving rollers, which make a certain angle with each other so as to stretch the fabric, so that, in the case of said rollers getting ever so slightly out of order, may result in the fabric being fed obliquely and the thread drawing tool consequently operating under bad conditions.

Lastly, the feed of the fabric can be given only

a limited number of predetermined values which depend upon the construction of the machine.

The object of the present invention is to obviate these various drawbacks through an arrangement based upon the following principles and a practical embodiment of which will be herein-after described, said principles being that:

The feed of the fabric is obtained through rollers disposed in strictly parallel relation with respect to each other and which are given a discontinuous rotary motion, the amplitude or rate of which can be adjusted in a continuous manner, said rollers being partly engaged into the work plate, so as to maintain the fabric stationary before, during and after the action of the thread drawing tool. Said rollers have their periphery made of a material which does not allow the fabric to slide thereon, for instance of india rubber.

The fabric is stretched by means of other rollers which are driven together with the feeding rollers, so as not to interfere with the feed. Said stretching rollers are smooth so as to allow the fabric to slide thereon.

The sectional outlines of the last mentioned rollers and of the work plate are such as to progressively increase the total length of the sinuous line along which the fabric is stretched between the feed rollers, from the time at which the fabric is caught by said feed rollers to the time at which the thread drawing tool has completed its work.

That increase in length progressively stretches the fabric up to a high tension.

All these organs can be combined in such manner as to be carried by a common main support which may be lifted like an ordinary presser foot.

Said feeding and stretching arrangement leaves the under face of the table of the machine entirely free, which make it possible to utilize without difficulty any cutter knife system, and in particular a knife adapted to rotate about a vertical axis (that is an axis at right angles to the fabric) without complicating it with a reciprocating vertical motion as described in the U. S. Patent No. 1,895,995 to G. Jalbert, January 31, 1933, for Improvements in machines for drawing the threads of a fabric.

Preferred embodiments of the invention will be herein-after described with reference to the accompanying drawings, given merely by way of example, and in which:

Fig. 1 is a front view of the part of the head

of the machine which is located above the table, some parts being shown in section;

Fig. 2 is an end view partly in section of the same mechanism;

5 Fig. 2a is a sectional view on an enlarged scale on the line 2a—2a of Fig. 2.

Fig. 3 is a view analogous to Fig. 1, that is a front view, of the presser foot, which serves to both feed and stretch the fabric, the work plate 10 and the table of the machine being cut on the line P P' of Fig. 2;

Fig. 4 is a view analogous to Fig. 3, but seen from the back of the machine, the same parts, viz. the work plate and the table of the machine being supposed to be cut;

Fig. 5 is a corresponding side view;

Figs. 6 and 11 are an end view and a plan view, respectively, of the work plate with its counter blade and the stretching ridges;

20 Figs. 7, 8 and 9 are sectional views taken in planes Ox, Oy, and Op' of Fig. 5 respectively, of the fabric feeding and stretching devices and of the fabric itself.

Fig. 10 is a sectional view on the line 10—10 of 25 Fig. 11.

Figs. 12 and 13 are two diagrammatical views of the fabric during the operation of the machine, according as the fabric is well stretched or not, respectively.

30 The main shaft 1 of the machine, which is driven by wheel 2, imparts to supporting bar 5 of the thread drawing tool 6, and therefore to said thread drawing tool, a reciprocating vertical motion through the intermediary of crank plate 3 and of connecting rod 4 (Fig. 2).

The fabric feeding devices consist of wheels 23, 23' which partly engage a cylindrical groove provided in plate 25 which serves to support the fabric.

40 The fabric stretching organs comprise:

On the one hand two ridges 26, 26' provided in the cylindrical groove of plate 25 and the front ends of which are bevelled, as shown at b, b' in Figures 10 and 11.

45 On the other hand two wheels 24, 24' provided with circular grooves 29, 29' in register with ridges 26, 26'.

Said wheels are keyed on the same shaft as feeding wheels 23, 23'.

50 The thread cutting organs comprise: On the one hand a cutter knife 28 (Fig. 10), on the other hand counter-blade 27, which corresponds in shape to the cylindrical part of plate 25, and against which the cutter knife is applied in order to cut the threads.

Ridges 26, 26' are disposed on either side of counter blade 27, and as close to it as it is possible.

60 Feeding wheels 23, 23' and wheels 24, 24' are rotated by main shaft 1 (as shown in Fig. 2) through eccentric 7 keyed on said shaft and actuating through connecting rod 8 sector-shaped lever 9. Said lever 9 drives, through a clutch of the free-wheel type, shaft 12, which therefore rotates

65 through a certain angle for each turn of main shaft 1. The rotation of shaft 12 is imparted to shaft 15 through helicoidal gears 13 and 14, and shaft 15 transmits that movement to wheels 23 and 24 (see Figs. 4 and 5) through worm gears 16 and 17 and pinions 18 and 18', rigidly carried

70 by the shaft that carries pinion 17, and which in turn drives gear wheels 19 and 19' integral with wheels 23 and 23'.

The whole of wheels 23 and 23', 24 and 24', and 75 of pinions 19 and 19' is mounted on a spindle

adapted to rotate freely in main support 20. Said support is secured to bar 21 and is urged against plate 25 by the action of spring 22.

The point 10 at which connecting rod 8 is secured to lever 9 can be varied along said lever, so that the angle through which shaft 12 is rotated for every revolution of main shaft 1, and accordingly the angle through which rollers 23, 23' are rotated, can be varied at will. To this effect, sector-shaped lever 9 is provided with 10 a groove in which is engaged the head of a stud 58 extending through a sleeve 59 and the end of which is screw threaded so as to receive a wing nut 60 by means of which it is fixed to lever 9 at a given point thereof. The end of rod 8 is piv- 15 oted about said sleeve 59.

The peripheries 30, 30' of wheels 23, 23', respectively, are preferably made of india-rubber as shown in Figs. 7 to 9 inclusive.

The operation of the device is as follows: 20 The fabric is inserted under rollers 23 and 23' when it reaches line AA' (Fig. 11).

It is then driven by said rollers and conforms with the cylindrical shape of plate 25 between AA' and BB'. As rollers 23 and 23' are applied 25 against the work plate by the pressure of support 20, the fabric cannot slide with respect to said rollers.

When the fabric reaches generatrix YY' of 30 said cylindrical portion of plate 25, it moves along the bevelled portions b, b' of ridges 26, 26' which give to it, in the transverse direction, a sinuous profile the total length of which increases progressively, and therefore progressively increase its tension. Consequently, when the 35 fabric reaches plane P of the thread drawing tool, it is stretched to the maximum extent and is in the best condition for a perfect drawing of the threads. Said stretching of the fabric takes place without injuring it in the least since 40 smooth wheels 24 and 24' do not oppose the necessary sliding movement of the fabric.

Owing to the fact that ridges 26 and 26' extend beyond plane PP', the fabric remains also perfectly well stretched after the drawing of the 45 threads, which has a certain importance.

For if, as shown in Fig. 13, the fabric were no longer well stretched, the threads at right angles to the drawn threads would risk, by sagging, to pass through slot F (Fig. 11) through which the 50 thread drawing tool is adapted to pass, and they would accordingly be cut off by cutter knife 28.

The shape of the smooth wheels or rollers and of the work plate might be different, provided that the combination of their profiles involves a 55 progressive increase of the total length of the sinuous line along which the fabric is stretched in its portion comprised between the feeding rollers, so as to suitably increase the tension of said fabric.

In a general manner, while the foregoing has disclosed what is believed to be a preferred and efficient embodiment of the invention, it should be well understood that the invention should not be limited thereto as there might be changes 65 made in the arrangement disposition and form of the parts without departing from the principle of the invention as comprehended within the scope of the appended claims.

What I claim is:

1. In a machine for drawing the threads from fabrics, a fabric feeding and stretching device comprising in combination, a work plate having a cylindrical shallow groove at right angles to the direction of feed, two parallel rollers coaxially 75

- disposed with respect to said cylindrical groove and the peripheries of which are arranged to fit in said groove against the bottom thereof, said peripheries being made of a material upon which 5 the fabric does not slide, and means for imparting a discontinuous feed motion to said rollers, whereby the fabric is tightly held between said cylindrical groove and said rollers and caused to move together with said rollers.
- 10 2. In a machine for drawing the threads from fabrics, a fabric feeding and stretching device comprising in combination, a work plate having a cylindrical shallow groove in its upper face at right angles to the direction of feed, two parallel 15 rollers coaxially disposed with respect to said cylindrical groove and the peripheries of which are arranged to fit in said groove against the bottom thereof, said peripheries being made of india-rubber, means for imparting a discontinuous feed 20 motion to said rollers, whereby the fabric is tightly held between said cylindrical groove and said rollers and caused to move together with said rollers, and means, interposed between said rollers, for causing the fabric to assume a sinuous 25 shape in a direction at right angles to the direction of feed, whereby the tension thereof is increased.
3. In a machine for drawing the threads from fabrics, a fabric feeding and stretching device 30 comprising in combination, a work plate having a cylindrical shallow groove at right angles to the direction of feed, two parallel rollers coaxially disposed with respect to said cylindrical groove and the peripheries of which are arranged 35 to fit in said groove against the bottom thereof, said peripheries being made of a material upon which the fabric does not slide, means for imparting a discontinuous feed motion to said rollers, whereby the fabric is tightly held between said 40 cylindrical groove and said rollers, and caused to move together with said rollers, two arcuate ridges in said groove at right angles to the axis thereof and close to said rollers respectively, and two smooth rollers parallel with the first mentioned rollers and adapted to cooperate with said 45 ridges for causing the fabric to assume a sinuous shape in a direction at right angles to the direction of feed, whereby the tension thereof is increased.
4. A fabric feeding and stretching device according to claim 3 in which the smooth rollers are adapted to bear against the inner faces of said ridges respectively. 5
5. A fabric feeding and stretching device according to claim 3 in which the smooth rollers are adapted to bear against the inner faces of said ridges respectively, said device further comprising means for imparting to said smooth rollers the same discontinuous feed motion as to the first named rollers. 10
6. In a machine for drawing threads from fabrics, a fabric feeding and stretching device comprising in combination, a work plate having in its upper face a cylindrical shallow groove at right angles to the direction of feed, two parallel 15 rollers having a diameter equal to that of said cylindrical portion of the work plate, having their common axis parallel to the generatrices of said cylindrical portion, a support for said rollers, means for urging said support in a downward direction so as to press the peripheries of said 20 rollers against said groove, and means for imparting a discontinuous feed motion to said rollers, the periphery of said rollers being made of a material which does not slide on the fabric, whereby the fabric is tightly held between said 25 cylindrical groove and said rollers and caused to move together with said rollers. 30
7. A fabric feeding and stretching device according to claim 6 in which the means for imparting a discontinuous feed motion to said rollers comprise a main shaft, a secondary shaft, a lever pivotally mounted about the axis of said secondary shaft, a clutch for connecting said lever to said secondary shaft for one direction of movement of said lever, means operatively connected to said main shaft for imparting a rocking motion to said lever, and a plurality of gears for transmitting the movement of said secondary shaft to said rollers. 35
